(57) **CLAIM**

The ornamental design for a firearm sling mount, as shown and described.

DESCRIPTION

FIG. 1 is a perspective view of a firearm sling mount showing my new design;

FIG. 2 is a top plan view of the firearm sling mount;

FIG. 3 is a left side elevation view of the firearm sling mount;

FIG. 4 is a front elevation view of the firearm sling mount;

FIG. 5 is a back elevation view of the firearm sling mount;

FIG. 6 is a right side elevation view of the firearm sling mount; and,

FIG. 7 is a top plan view of the firearm sling mount.

The portions of the firearm sling mount shown in broken lines form no part of the claimed design.

1 Claim, 2 Drawing Sheets
